LAMP TESTER

Filed April 27, 1928

UNITED STATES PATENT OFFICE

WILLIAM F. HAYES, OF PROVIDENCE, RHODE ISLAND

LAMP TESTER

Application filed April 27, 1928. Serial No. 273,247.

This invention relates to testing devices of the type adapted to cause illumination of incandescent lamps.

An object of the invention is to provide a lamp tester for simultaneously illuminating a plurality of incandescent lamps mounted in a carrier.

Another object is to produce an efficient, strong and durable lamp tester which is simple in construction and inexpensive to manufacture.

With these and other objects in view, the invention consists of certain novel features of construction, as will be more fully described, and particularly pointed out in the appended claims.

In the accompanying drawings:

Figure 1 is a side elevation of a lamp tester constructed according to the invention;

Figure 2 is a perspective of one of the sections thereof;

Figure 3 is a similar view of the other section thereof;

Figure 4 is a perspective showing the sections assembled and illustrating the underlying structure by broken lines;

Figures 5, 6, 7 and 8 are vertical sections taken along the lines 5-5, 6-6, 7-7 and 8-8 respectively of Figure 1;

Figure 9 is a plan of a lamp carrier showing a plurality of lamps mounted therein, and illustrating the application of my invention thereto;

Figure 10 is a vertical transverse section through the carrier shown in Figure 9, illustrating by broken lines the application of my device thereto; and

Figure 11 is a diagrammatic view of the electric circuit.

It is found in practice desirable to simultaneously test a group of lamps mounted in a carrier, such as lamp kits containing a plurality of lamps whose bases are disposed in juxtaposition to each other, without requiring the removal of the lamps from the carriers, in order to determine whether or not the lamps will function properly. Accordingly, the present invention consists of a device adapted to be connected to a suitable source of current and to bridge all of the lamps of a group or

set simultaneously to cause the current to flow through the lamps and illuminate the same, and the following is a detail description of one construction by which these advantageous results may be accomplished.

With reference to the drawings, incandescent electric lamps 11, 12, 13 and 14 may be mounted in a carrier consisting of a bottom section 15 and a top section 16 hinged thereto, as indicated at 17, whereby the top can be folded over the bottom section to enclose the same. The lamps 11 and 12 are larger than the lamps 13 and 14, and all of the lamps are of the same type, that is, they have a single electrical contact.

The section 15 is provided with means for receiving the bases of the lamps whereby such lamps may be rigidly mounted in the carrier with the bulbs of the lamps oppositely disposed and spaced from the walls of the carrier. In the present instance, the mounting means includes pairs of U-shaped channels 18 and 19, which are slightly spaced apart and disposed parallel to each other lengthwise of the carrier. Each of the channels 18 and 19 have transverse slots so formed therein for receiving pins 21 projecting from the lamp bases.

Preferably, the channels 18 and 19 are made from a suitable length of sheet metal 80 bent to the form shown in Figure 10, with a depending U-portion 22 centrally disposed between the channels, and the slots 20 are so formed in each of the channels that the adjoining ends of the lamp bases will be spaced 85 a slight distance apart.

For the purpose of electrically connecting the bases of the lamps 11, 12, 13 and 14 while such lamps are mounted in the carrier, I have provided a device comprising an elongated body composed of four sections 24, 25, 26 and 27. These sections are made from suitable sheet insulating materials, the outer sections 24 and 25 being of thicker material than are the inner sections 26 and 27. The several sections are clamped together by means of screws 28.

The sections 26 and 27 are designed to carry means for bridging the several lamps to permit the flow of current therethrough, and 100

therefore the section 26 is provided with a longitudinal slot 29 extending from one end to a point near its opposite end, such slot being offset downwardly near the front end of the section, for a purpose to be hereinafter described.

At the front end of the section 26 there is a pair of spaced depending ears 30 and 31, these ears being formed as extensions of the material used in constructing the section. Slots 32 and 33 are respectively formed in the ears 30 and 31.

A strip of flexible metal is passed through the slot 32 and folded backwardly towards the opposite surface of the ear 30 to provide a contact member 34. One end of the member is riveted to the section 26 adjacent the end of the slot 29, as indicated at 35. The other end of the contact member provides a resilient finger on the opposite side of the ear. The end of an insulated conductor 36 is attached to the upper end of the contact member 34.

Similarly, another strip of flexible metal is passed through the slot 33 and bent in the manner just described to provide a contact member 37, the upper end of which is fastened to the section 26 adjacent to the slot 29 by means of a rivet 38, while the other or free end thereof provides a resilient finger on the opposite side of the ear 31. The conductor 36 is also attached to the upper end of the contact member 37. If so desired, the conductor 36 can be soldered to the contact members 34 and 37, or any other known means may be employed for connecting the two contact members in parallel with the conductor.

It should be noted that the free end portions of the contact members 34 and 37 are adapted to be compressed towards the faces of the ears, when the device is inserted between the adjoining lamp bases, as clearly shown in Figure 9.

The section 27 may have a configuration corresponding to the sections 24 and 25, and this section is formed with an elongated slot 39 extending longitudinally thereof, and having its lower edge offset upwardly, as indicated at 40.

A flexible metal plate 41, bent into the form of an L, is attached to the section 27 near the end of the slot 39, the lower portion of the plate projecting below the section a suitable distance so that when the device is applied to a lamp carrier the bottom of the plate will contact with either one of the sides of the channels 18 and 19. One end of an insulated conductor 42 is attached to the upper portion of the plate 41, by solder or any other suitable means.

When the sections 26 and 27 are assembled in the manner shown in Figure 4, the conductors 36 and 42 are disposed within the slots 29 and 39 respectively. However, due to the spaced relation of the offset portions of the

slots, the exposed ends of the conductors will be insulated from each other, as will be readily understood, and the sections 24 and 25 will cover said slots (see Figures 7 and 8).

It will therefore be seen that I have provided a device comprising a pair of spaced contact members 34 and 37 adapted to be inserted between the adjoining spaced ends of pairs of lamps, and between the members 34 and 37, there is another contact member 41 adapted to engage the portion of the lamp carrier between the pairs of lamps and provide a ground therefor.

In Figure 11 I have shown a circuit wherein the ends of the conductors 36 and 42 are respectively connected to the terminals of a battery 43, the contact members 34 and 37 being in engagement with the lamp bases, and the plate 41 grounded.

Obviously, the type of carrier for the lamps is immaterial, because the invention can be used with any arrangement of lamps in which the lamps are so mounted that their bases can be bridged by a single contact member in the manner hereinbefore described.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A connector device for testing lamps comprising a body of insulating material having a pair of members extending beyond the margin of the body and in closely spaced relation, said members carrying two contacts connected in parallel.

2. A connector device for testing lamps comprising a body formed of insulated sections, a pair of contact members mounted in parallel in one section, and a single contact member mounted in the other of said sections.

3. A connector device for testing lamps comprising a sectional body, one of the sections thereof having spaced depending ears, flexible contact members mounted in the said ears and disposed on both sides thereof, and a contact member depending from the body and disposed intermediate the said ears.

4. A connector device for testing lamps comprising a sectional body, one of the sections thereof having spaced depending ears, contact members mounted in said ears and disposed on both sides thereof, a contact member depending from the body and insulated from the said ear contact members, and means for electrically connecting the said contact members whereby the said ear contact members will be connected in parallel.

5. A device for testing a pair of lamps each having a single contact and mounted with their bases in juxtaposition, comprising a portable connector body of insulated material

having contact members for bridging the said lamp bases and a ground contact member, and means for supplying electric current to the said contact members.

6. A connector device for testing lamps comprising a body formed of a plurality of plates of insulating material, two of the said plates being longitudinally slotted and one having depending ears, electrical contact members carried by said ears, a grounding contact member carried by another of said second plate and disposed intermediate the said ears on the first plate, electrical conductors disposed within the said slots, one of said conductors being secured to both of the said contact members and the other conductor being connected to the said ground member, plates covering the faces of the said first and second plates and inclosing the said slots, and means for securing all of the said plates together.

7. A connector device for testing lamps comprising a plate of insulating material longitudinally slotted, ears depending from the edge of the material adjacent to the end of the slot, a slot formed in each of the ears, a contact member fastened to the plate and extending thru the slot, said contact member being disposed on both sides of the said ears, a second plate of insulating material having a slot formed longitudinally therein, a ground member fastened to the said second plate and being disposed intermediate the said ears, plates of insulating material disposed on opposite sides of the said first and second plates, electrical conductors disposed within the said slots and connected to the said contact and ground members, said contact members being connected in parallel with a single conductor, and means for securing the said plates together.

In testimony whereof I affix my signature.
WILLIAM F. HAYES.
